UNITED STATES PATENT OFFICE.

BRADFORD S. PIERCE, OF NEW BEDFORD, AND MASON R. PIERCE, OF MANSFIELD, MASSACHUSETTS.

MACHINE FOR MAKING DRAIN-PIPES.

Specification forming part of Letters Patent No. 23,703, dated April 19, 1859; Reissued February 28, 1865, No. 1,897.

To all whom it may concern:

Be it known that we, BRADFORD S. PIERCE, of New Bedford, and MASON R. PIERCE, of Mansfield, both in the county of Bristol, 5 State of Massachusetts, have invented a new and useful Improvement in Machines for the Manufacture of a Pipe or Tube to be Used for Drains or Flues; and we do hereby declare that the following is a full, clear, 10 and exact description of the construction and operation of the same, reference being had to the annexed drawings, making part of this specification, in which—

Figure 1 is a perspective view. Fig. 2 is 15 a longitudinal elevation. Fig. 3 is a plan. Fig. 4 is a core reliever.

To enable others to understand the manner of constructing and operating our machine we proceed to describe the same, with 20 reference to the figures and letters.

Letters A A, represent a rotary platform, letter A, a cistern, letter B a water pipe, letter C, a faucet, letter D a hopper, letter E a shaft, letters F and G the mixing pins and 25 float, letter H the crank connected with the mixing shaft, letter I a stop, letter J a pin, letter K a revolving cylinder, letter L a spout, letter M a gage, letter N the double rack guides, letter O the double rack, letter 30 P the concave piston; letter Q a geared wheel, letter R a pinion, letter S a longitudinal pinion, letter T a pinion shaft, letter U a crank, letter V a single rack, letters W X, a wheel and pinion, letters Y, Z the 35 driving and driven shaft, letter a a hand wheel used to move the rotary platform, letter b a shipper used to disconnect the catch c from the platform, letter d is a driving crank, letter e represents the eight 40 perforations in the platform admissive of the different sizes of core socket, letter f the core socket, letter g an upright post with a lever h attached, letter i a plunger, letter j a hand working the lever h, letter k 45 the interior section of the pipe, letter l the two pieces of wood or metal attached to the metallic case, letter m the five conical rolls upon which the rotary platform revolves, letter n a clamp or fastener to hold the case 50 firmly together, letter o a bevel ring which forms the concaved end of the pipe, letter p is a stay which holds the core at an equal

distance from the case while the mold is being filled, letter r is a core constructed of 55 wood or metal, letter s is a metallic case, letter t is a circular hopper to aid in filling the mold, letter u an opening in the revolving cylinder, letter v two sections of pipe connected, letters a a represent the thickness 60 of the pipe.

To operate our machine we place the ingredients of which the pipe is to be made in the cylinder K, in its proportional parts we then mix them together by turning the crank H, when this is completed we upset 65 the cylinder and empty its contents into the spout L where it is removed with a shovel to the hopper, which is placed upon the top of the mold. The concave piston is at intervals forced upon the ingredients by 70 means of the crank U, several times while the mold is being filled. The last stroke of the piston forms the convex end of the pipe which is an exact counter shape to that formed by the bevel ring o. The mold being filled the hand wheel a is revolved to 75 convey the filled mold toward the core reliever and bring the second mold in a position, beneath the piston to be filled as before and the same operation is repeated with 80 the entire set of molds. When the first mold comes directly under the core reliever the crank d is then used to force down the rack or plunger, upon the core P and thrust the same through the socket e and platform into 85 a pit below. The platform is then revolved to fill the next mold. When the first filled mold is brought in the position between the reliever and hopper it is removed to be discharged, when it may be replaced. 90

Our mold may be used without the aid of the other parts of the machine as shown at Fig. 4. The mold with its socket is placed upon a suitable level base when the ingredients after being properly mixed can be 95 filled in and rammed by hand. And the core is afterward relieved or discharged by the aid of a lever and pendent bar as shown in Fig. 4. In order to keep the top of the core in proper position during the filling process 100 the double ring clasp c, on which a hopper may be placed, is applied to the top of the mold and core pin.

Having thus described our improvement

in pipe machines, what we claim and desire to secure by Letters Patent is—

1. The arrangement of the mixing apparatus, pressing and core relieving devices above the platform for conveying the molds in the manner and for the purpose specified.

2. Also the arrangement of the core socket upon the revolving disk to receive the core

and the mold, with a provision for discharging the core through the platform all in the manner and for the purpose specified.

BRADFORD S. PIERCE.
